DRAFT PRODUCING AND REGULATING MEANS

Newton Frank Lane, Decatur, Ill.

Application November 20, 1939, Serial No. 305,323

5 Claims. (Cl. 236—14)

This invention relates to improvements in draft-producing and regulating means, and more particularly to such means as utilized for producing a controlled and balanced drafting effect in locomotive type boilers, through the use of automatic control facilities for the draft-producing means.

This application is a continuation-in-part of my copending application Serial No. 143,463, filed May 19, 1937, which issued December 26, 1939, as Letters Patent 2,184,647, entitled Drafting of locomotives. The present application is directed particularly to the features of the invention relating to the control of quantity of drafting air as well as control of draft balance, in accordance with boiler steaming requirements and a furnace condition, such as a variable draft pressure in a predetermined zone of the boiler assembly.

It is a major object of the present invention to provide a fully automatic draft arrangement and draft control system, which operate responsively to boiler steam pressure or boiler steaming requirements, and also responsively to draft conditions to influence the draft-producing means utilized in connection with locomotive type boilers.

A number of attempts have been made in the past, but with no degree of success, to draft locomotive type boilers mechanically through the use of an induced draft fan or blower, generally located in or adjacent to the smoke box. It has also been attempted to augment the volume of air utilized for combustion, by the installation of forced draft fans or blowers of various types, serving to introduce the combustion air under a positive pressure, through or beneath the grate bars. Neither of these devices or methods is, considered alone, fully satisfactory for the purpose of drafting locomotive type boilers, largely because of the widely varying pressure conditions existing between the zones in and adjacent to the fire box, and those zones in which the air, charged with solid particles resulting from combustion, exists at a high temperature, as in the smoke box. With the use of a forced draft system alone, the zones of combustion are put under a substantial positive pressure, creating a tendency at times for the gases and flames to be driven out through the fire door. On the other hand, utilizing only an induced draft blower, there results a partial vacuum in the zone of combustion. Thus at the numerous times of opening the fire door, there results a detrimental inrush of cold air which reduces the temperature of the gases of combustion and reduces the heat otherwise

available to generate steam. It is accordingly an additional object of the present invention so to regulate the speeds, and hence the displacements of the fore and aft blowers, that there is maintained a volume and flow of air through the combustion zone which consists of only a desirable excess over combustion requirements, the displacement capacities of the two blowers being so proportioned that although combustion chamber pressures fluctuate within small limits, there is never any subatmospheric condition at the fire door. This arrangement results in what may, for convenience, be termed a balanced draft system.

15 It is a still further important object of the invention to provide, as a part of or adjunctively to a balanced draft system of the type described, a full automatic control arrangement therefor, whereby the speeds and displacements of the 20 forced draft and induced draft blowers may be not only proportioned correctly, but may be varied directly and automatically in keeping with steaming requirements, as well as in keeping with a furnace condition, such as draft requirements or draft pressure.

Still further objects of the invention will be noted from the following detailed description of a preferred embodiment of the draft-regulating and balancing agencies, as well as from the accompanying drawing, which consists of a single figure, showing in the upper portion, a diagrammatic view of a locomotive boiler and cab structure in which is indicated a preferred physical disposition of certain of the control instruments 30 as well as the induced-draft blower and turbine and forced-draft blower and turbine, the remainder of the figure consisting of a partly diagrammatic and partly physical representation of the electropneumatic control features characterizing the selected embodiment of the invention.

Referring now by characters of reference to the drawing, the boiler shell is indicated generally at 10, and the fire box at 11. Below the grate bars (not shown), is a substantially air-tight ash pan 12 into which is directed the discharge pipe 13 of a forced draft blower 14, impelled by a high-speed steam turbine 15. Two or more of the turbine-blower assemblies 14—15 may, if desired, be employed.

50 In the front end of the locomotive boiler assembly, specifically in the smoke box 16 of the example shown, is a housing 17 for a high speed steam turbine. For purposes of the present schematic representation the housing 17 may be taken as representing the turbine itself, and

which is operatively connected to an induced draft blower 20. This is shown as consisting of a propeller type fan located just inwardly of the lower end of an elbow-shaped fitting 21 directed to the boiler stack 22. The fitting 21 is provided with an extension 23 connecting into the exhaust saddle of the locomotive, and in operation, the blast of air and gases emitted from the induced draft blower 20 through the stack, exhibits a substantial eductive effect on the connection 23, thus serving markedly and in an improved manner to reduce back pressure in the exhaust passages.

Disposed in an overfire zone adjacent the fire arch, is a hollow stay-bolt connection 24. The tubular element 24 communicates with a line of piping 140 and 141 connecting to the apparatus for automatic control of the drafting system in accordance with draft pressures in this zone, all as hereinafter more fully described.

In the present example, the cab of the locomotive, indicated generally at 26, is shown in longitudinal section in order better to reveal the physical location of certain of the control instruments and agencies hereinafter more particularly described.

It will be understood that the forced draft blower turbine 15 and the induced draft blower turbine 17 are supplied with suitable steam supply and exhaust lines which, for clearness of illustration, have been omitted from the diagrammatic figure of the locomotive in the upper part of the drawing, although certain of the piping elements are hereinafter referred to in connection with the control apparatus.

Referring now to the preferred form of the control elements and their assembly, the system in the selected example being of electro-magnetic and pneumatic type, the system will be described by utilization of the same reference characters employed in the parent application, Serial No. 143,463, now Patent No. 2,184,647, in order to facilitate cross reference between that application and the present.

Proceeding now to a description of the means by which is effected an automatic control of the blowers in keeping with the steam pressure or steaming requirements of the boiler, it is seen that this type of control involves, at least in part, an influence of the main steam supply, a conduit for this purpose being indicated at 90, which is connected into the dry pipe or steam fountain (not shown), the pipe 90 serving directly to affect a control unit designated generally as 91. This unit is conveniently of a type involving a metal bellows indicated at 92, connected to the boiler as through the pipe 90, and through a lever connection 93, serves to actuate a pendulum-type control lever 94, pivotally mounted on a control panel 95. The lever 94 includes a pair of horizontal arms provided at their extremities with contacts 93 and 81. The length of the aligned horizontal arms of this lever is so selected, relative to the distance between a pair of fixed contacts 100 and 101, that when the lever is in its mid-position, neither of the switches 93—100 or 81—101 is closed. When, however, the lever is moved to the right or the left, the contact 93 or 81 as it approaches the adjacent stationary contact, serves to close the circuit. Each of the switches is illustrated only diagrammatically, any one of a number of suitable types of switches now available being suitable for this purpose.

The electrical circuit may be considered as hav-

ing its origin in either of a pair of supply leads 105 and 106 taken with a ground leg of the circuit. The leads are conveniently connected to the usual 32 volt supply system of the locomotive, and accordingly may be energized through the generator or storage batteries, or both.

The circuits originating in the control leads 105 and 106, are continued beyond the control panel designated generally at 110, through a pair of conductors 111 and 112, a ground wire 113 being provided in the circuit relation indicated, and electrically connected to the lever 94 in the example disclosed.

The leads 111 and 112 are continued into a control panel 115, the latter being provided with a pivotally mounted, pendulum-type switch lever 116, provided similarly to the lever 94, with horizontal arms, the extremities of which carry contacts 117 and 118, serving after the manner of the elements 98, 81 to control the circuits through a pair of switch contacts indicated at 119 and 120, respectively arranged in the lines 112 and 111. The switches 117—119 and 118—120 may be similar in design and capacity to the switches associated with the panel 95. Beyond the switches on the panel 115, the circuits are continued through leads 122 and 123, a ground wire 124 being provided for return purposes, and a ground connection effected as at 125. It will have appeared that the control circuit is of the type known as a single wire system, in which one side of each circuit is completed through a grounded leg which may conveniently consist, in part, of the metal portions of the locomotive structure and associated parts.

There is by preference mounted on the control panel 115, and operatively connected to the pendulum lever 116, a variable volume control chamber indicated at 130, and provided, for example, with a movable diaphragm 131, or in lieu thereof a piston (not shown), or some equivalent of the diaphragm or piston. To the diaphragm, for example, is conducted a control rod 132 pivotally connected to the lever 116, the movement of this lever under the influence of the diaphragm, being opposed by a variably-loaded compression spring 135, the loading of which is subject to adjustment as through threaded elements and lock nuts, the assembly of which is indicated at 136. The variable volume control chamber 130 is supplied internally with air under pressure through a conduit 140, which has its origin or entrance end, in the boiler structure at such location as to maintain the conduit under a pressure which varies directly with the variation in overfire draft supply, the entrance end of pipe 140 being, in the disclosed example, in the hollow stay-bolt 24. For convenience of providing a visual indication of the pressure in the zones over or beyond the fire, the conduit 140 may be branched and continued as at 141, to a pressure gauge 142, preferably located in the cab as shown, or at some other point for convenient visual indication to the engineer or fireman.

The control circuits are each completed beyond the panel 115, through the control wires 122 and 123, the former being connected to a pair of similarly disposed solenoid windings 145 and 146, for the energization thereof, the return circuit from each such winding being completed through the leads 147 and 148 connected to the ground lead 124, grounded at 125. In similar manner, the lead 123 is connected to a pair of similarly disposed electromagnets or solenoids

149 and 150, the return connections from which are completed through the conductors 147 and 148 to the ground at 125. It will have appeared that the solenoids or electromagnets are related in pairs, one pair comprising the magnets 145 and 149, and the other comprised of solenoids 146 and 150. Each of the pairs of magnets is provided with a common, double-end armature structure indicated generally at 151 and 152, and the armatures of each such structure connected through plungers 153 and 154 to an adjacent air control valve of piston and cylinder type. These air control valves include a piston 155 operating in a cylinder 156 on the one side, and a piston 157 operating in a cylinder 158, on the other side. The cylinders 156 and 158 are of double-end type, the cylinders being provided with air under pressure, as from the brake system of the locomotive, through air inlet pipes 160 supplying the cylinder 156, and 161 supplying cylinder 158, the pipes 160 and 161 being, for example, connected into the air reservoir (not shown) of the locomotive. Each cylinder is provided with a pair of outlets respectively near the upper and lower ends of the valve, these outlets being indicated in the control for the forced draft turbines, at 170 and 171, and in connection with the cylinder 158 serving to control the induced draft blower turbine, at 172 and 173.

The paired air discharge tubes or conduits from each valve cylinder, are connected respectively to the upper and lower ends of a double-ended cylinder-and-piston control unit, or air servo-motor, the motor cylinders being indicated at 176, for the forced draft turbine control, and 177 for the induced draft turbine control. These cylinders are each provided with a power piston, the pistons being designated respectively at 178 and 179.

Each power piston is connected through a rod, such as 185 or 186, thence through a pivotal connection 187 and 188, to a steam valve. The two steam valves illustrated are preferably of so-called chronometer type, providing a plurality of steam-admission passages through the body of the valve, which are graduated and so arranged that the first position of each valve provides an idling regulation of the associated turbine or turbines, while the remainder of the positions provide, in sequence, for augmenting the steam supply to, and hence serve to enhance the air displacement by the turbines controlled therethrough. Through the provision of links such as 190 and 191, the movements of the servo-motor pistons are translated to the valve actuating arms 195 and 196, operatively associated, respectively, with the valve bodies 197 and 198. The former of these serves to control the flow of steam through a boiler-connected steam supply pipe 199 and a forced-draft turbine supply pipe 200, and the latter valve controls the flow of steam through a boiler-connected steam supply pipe 201, thence to the supply line to the induced draft turbine, indicated at 202.

It has been found convenient in practice to provide the steam supply pipe 200 under the control of the valve 197, with at least a pair of branches, one thereof such as 205 leading to the steam supply for the stoker drive, and another shown at 206 being directed to the forced-draft turbines. If desired, hand valves 207 and 208 may be utilized for manual regulation or proportioning of the flow of steam through the respective branches 205 and 206.

The operation of the control system may be

briefly reviewed by noting that, as the steam pressure increases in the boiler and hence in the conduit 90, and hence that, as the steaming requirements of the boiler decrease, the increased pressure will influence the unit 91 in a manner to swing the lever 94 to the left, thus serving to bring the contact 98 into engagement with the stationary contact 100, thus completing the circuit through the ground and through the control legs 106 and 112, thence, assuming the switch 117-119 to be closed, through the lead 122 so as to energize the upper coils 145 and 146 of the solenoid valve-operating assembly. This will cause the armature assemblies 151 and 152 to be actuated upwardly, into the positions shown by the drawing, raising the pistons 155 and 157, closing the inlets 170 and 172 to the servo-motors, but opening the inlets 171 and 173. This actuation will have the effect of putting the air pressure from the air supply system against the lower faces of pistons 178 and 179 of the servo-motors, with the effect of raising, in the positions shown, the valve-actuating levers 195 and 196. If the circuit remains closed as indicated, for an appreciable time, the valves will thus be actuated toward steam-restricting positions, and will be brought to positions in which the steam supply is only sufficient to cause the turbines and blowers to operate at idling speed.

It will have been noted that this actuation is dependent upon the closed position of switch 116-117, this switch being closed only in response to a predetermined but substantial air pressure in the overfire zone. It is accordingly seen that the controls are responsive primarily to the steam supply and boiler steaming requirements, and also secondarily subjected to the influence of the overfire draft pressure. This is true since the one of the switches carried by panel 115, which is closed, the switches being operable only one at a time or selectively, is determined by draft conditions.

Assuming now an opposite set of conditions to prevail, namely a relatively reduced steam pressure and a relatively reduced draft pressure, the influence of the bellows unit 91 will operate to close the switch 81-101 and permit the switch 98-100 to open. Assuming the switch 81-101 to be closed, and assuming a low draft condition to prevail in the overfire zone, so that switch 118-120 is closed, a different control circuit will now be completed, one side through the ground, and the other side through the leads 105, 111 and 123, so that the coils 149 and 150 become energized, at the same time coils 145 and 146 being deenergized. This will result in a movement of the armatures 151 and 152 to their lowermost positions in the figure, in a manner to move the valve pistons 155 and 157 in a direction toward the opposite ends of the valve cylinders. Under this condition, air is excluded from the lower end of the motor cylinders and admitted to the upper ends thereof, assuming them to be mounted in the positions shown. Thus the valve levers 195 and 196 will be actuated to a steam-admitting position, the extent of their opening depending upon the amount and duration of air admission to the servo-motor, as influenced by the controls described. This set of conditions serves to increase the speed of the forced draft turbines as well as the speed of the induced draft turbine in a manner to increase the draft supply, and similarly the steaming rate. It is to be observed that the increase or decrease of turbine and blower speeds, is always such as to keep the induced-

draft and forced-draft units correctly proportioned in output.

It is preferred to provide for an adjustment of the extent of actuation and proportionate movement of the valve-operating levers 195 and 196, as through the provision of a number of openings 195A and 196A, selectively utilized for the connection of a pivot pin on each of the links 190 or 191 to the associated valve lever. It will clearly appear from the drawing that as the links 190 or 191 are set farther inwardly, or more closely to the pivots of the associated valve levers 195 or 196, a given movement of the associated air piston will serve to effect a greater angular movement of the throttle valve element 15 controlled thereby. This facility for adjusting the relative range of movements of the chronometer valves, is of importance in the present assembly in that it enables a given installation to be adjusted to proportion the speeds and hence the displacements of the induced and forced draft blowers to each other, throughout the range of their throttling control. This feature enables the maintenance with considerable accuracy of a substantially balanced draft condition, irrespective of whether the drafting requirement be great or small. This feature also enables a compensating adjustment of the controls to care for differences in the different blower assemblies, as well as certain inherent differences necessary to be adjusted for in different types of locomotives, as well as individual differences found in different locomotives of any given type.

It is preferred so to set the control instruments such as the steam-pressure responsive unit 91, and the draft-responsive unit carried by panel 115, that an appreciable range of pressure occurs between opening and closing valve movements. This is preferably at least a five pound pressure differential, and in many cases it is advisable to provide for a ten pound difference in setting, so as to prevent unnecessary hunting of the controls in response to minor variations in steam pressure. Similarly, the setting of the draft responsive control avoids excessive changes in the control circuits and avoids needless control actuation in response to minor variations in draft pressures.

It is desirable in most installations, to provide for a manual control of the steam supply through the turbines, in case of failure of any part of the control system, or so as to enable the operator, as in an emergency, to meet extreme conditions by manually controlling the amount of draft. Among the instruments preferably so provided, is a master steam pressure control indicated at 209, a draft control for the forced draft fans shown at 210, and a chronometer type, hand throttle valve designated as 211. These are preferably disposed at a convenient point of access to the fireman, as on the left side of the cab 26, their positions as shown having been found convenient in practice.

While the exact physical location of many of the items of control apparatus heretofore described, is not material to the invention, it may for completeness be pointed out as advantageous and practical to locate the two master control units such as 91 and 115 in the cab for example 70 in the side-by-side arrangement suggested by the upper figure of the drawing showing these units located over the window on the fireman's side of the cab. It has been found advantageous prior to installation, to assemble the chronometer

5 valve, solenoid assembly and servo-motor for each of the blower systems, as a unit, each such unit, such as indicated at 220, preferably including, for example, the forced draft control elements comprising solenoids 145 and 149, together with valve 156 and air motor 176, lever 195 and chronometer valve 197, together with immediate piping and appurtenances. Similarly, the induced draft control agencies are assembled as a unit shown as to location at 221, and including the solenoids 146 and 150; the air valve 158, air motor 177, valve lever 196 and chronometer valve 198. A suggested and practical location of the units 220 and 221 is in the cab, under the fireman's seat in about the location shown in the upper portion of the drawing. Optionally, these units may be located elsewhere as desired, say under the engineer's seat in the cab.

20 It will have appeared that the system described serves to compensate for differences in fuel bed according to type of fuel being burned, and to compensate for other variations in specific operating conditions, so that the speeds of the fans are correctly proportioned, through an automatic control, at all times. Concurrently both fans are subject to control under the influence of steam pressure, and hence of steaming rate, as well as draft pressure. The ideal operating condition is, of course, to maintain the optimum steam and draft pressure to meet a given set of working conditions of the locomotive, and when desired, to maintain as high a pressure as possible without loss of steam through popping of the safety valve, which obviously results in inefficiency and loss of thermal values.

25 While the invention has been described by making specific reference to a presently preferred embodiment of the invention, the description is not to be understood in a limiting sense, since obviously many changes may be made within the intended scope of the invention as defined by the claims hereunto appended.

30 I claim as my invention:

40 1. In combination in a steam locomotive, a balanced draft producing and control system including a steam turbine-driven blower of forced-draft type, having its outlet ahead of the grates and adapted to force a supply of combustion air therethrough, a steam turbine-driven induced-draft blower located in the smoke box of the locomotive boiler, a fitting forming a discharge passage from the induced draft blower and so directed as to impart a steam eductive effect to the engine exhaust passages into the stack, and such that exhaust impulses coact in the draft-inducing action of the last said blower, the two blowers being so proportioned with respect to each other as to maintain in the drafting system between the blowers, a pressure substantially of the order of atmospheric; a control system for the blowers including an energized control circuit, a first pressure-responsive switch in said circuit having a loaded pressure-movable element subjected to draft pressure in an overfire zone, and hence influenced by effect on draft pressure, of exhaust and steam demand, a second, similar pressure-responsive switch subjected to boiler steam pressure, electromagnetic means in said control circuit, and a steam throttle valve for each of the steam turbines, and functional connections between said electromagnetic means and throttle valves.

45 2. In combination in a steam locomotive, a balanced draft producing and control system in-

cluding a turbine-driven blower of forced-draft type, having its outlet ahead of the grates and adapted to force a supply of combustion air therethrough, a turbine-driven induced-draft blower of substantially greater volume displacement capacity than the forced draft blower, and located in the smoke box of the locomotive boiler, a fitting forming a discharge passage from the induced draft blower, and so directioned as to impart a steam eductive effect to the engine exhaust passages into the stack, and so connected to the exhaust passages that the exhaust impulses coact with the induced draft blower in its draft inducing effect, and further coact with the induced draft blower in affecting the blower control system, the two blowers being so proportioned with respect to each other as to displacement capacity, as to maintain at all times during blower operation, a substantially balanced draft pressure condition between the grates and the induced-draft blower, and to maintain in the drafting system between the blowers, a pressure substantially of the order of atmospheric; a control system for the blowers including a first pressure-responsive apparatus having a loaded pressure-movable element subjected to draft pressure in an overfire zone and above the fire arch, and hence affected by fluctuations of draft pressure by reason of exhaust fluctuations and varying steam demand, a second pressure-responsive apparatus subjected to boiler steam pressure, electromagnetic means influenced by said pressure-responsive apparatus, separate fluid pressure control devices, each in individual throttling relation to the steam supply to one of the blowers, both said devices being subject to control of said electromagnetic means, and arranged to effect concurrent throttling actuation in the same direction, means for varying the proportionate throttling effect of said devices on the two blowers, as influenced by said electromagnetic means, and means for varying the loading and response of each said pressure-movable element, whereby to provide for variation in range of pressure influence on the blower turbines.

3. In a draft-producing and controlling system for locomotive boilers, an air displacement device or blower of forced-draft type arranged to supply air to the grates, a blower in the smoke box, and arranged to coact in the draft-inducing effect of the engine exhaust, a steam turbine in driving relation to each of said blowers, a throttle valve in the steam supply line of each turbine, directly controlling the admission of steam thereto, an air motor connected to each of said throttle valves, an electromagnetic control device connected with each air motor, an energized control circuit for said electromagnetic control devices, a pressure switch in said circuit, provided with fluid connections for response of the switch to changes in boiler steam pressure, and a second pressure switch in said control circuit, provided with fluid connections to effect its response to changes in draft pressure in an overfire zone, the exhaust connection into the smoke box, together with the smoke box blower and draft zone to which said second pressure switch is respon-

sive, being coactingly so arranged that said second switch is responsive in part to fluctuations in exhaust volume and hence responsive to fluctuations in steam demand.

4. In a draft-producing and controlling system for locomotive boilers, an air displacement device or blower of forced-draft type, arranged to supply air to the grates, a blower in the smoke box arranged to coact in the draft-inducing effect of the engine exhaust, a steam turbine in driving relation to each of said blowers, a throttle valve in the steam supply line of each turbine, directly controlling the admission of steam thereto, an air motor connected to each of said throttle valves, an electromagnetic control device connected with each air motor, an energized control circuit for said electromagnetic control devices, a pressure switch in said circuit, provided with fluid connections for response of the switch directly to changes in boiler steam pressure, and a second pressure switch in said control circuit, provided with fluid connections to effect its response to changes in draft pressure, the pressure switches being arranged in series in the control circuit, and the second pressure switch being connected for pressure response, to a zone in the draft system to render this switch responsive in part to changes in exhaust rate, and hence responsive also to variations in steam demand.

5. In a draft-producing and controlling system for locomotive boilers, an air blower of forced-draft type arranged to supply air to the grates, a blower in the smoke box arranged to coact with the engine exhaust in draft-inducing effect, a separate steam turbine in driving relation to each of said blowers, a throttle valve of modulating type in the steam supply line of each turbine directly controlling the admission of steam thereto, an air motor of double-end cylinder type, connected to each of said throttle valves, an electromagnetic control device of double-coil type connected with each air motor, a blower-accelerating circuit arranged to energize like coils of the electromagnetic control devices, a blower-retarding circuit connected to the remaining coils of the electromagnetic control devices, a pressure switch having a movable contact element provided with fluid connections for response of the switch directly to changes in boiler steam pressure and having separately engageable contacts respectively arranged in the accelerating circuit and the retarding circuit, a second pressure switch having a movable element and fluid connections thereto to effect its response to changes in draft pressure, and stationary contacts respectively arranged in the accelerating circuit and retarding circuit, with corresponding terminals of the first said switch and second said switch related in series, the movable element of said second pressure switch being connected for its pressure response, to a zone in the draft system to render said second switch responsive in part to changes in exhaust rate, and hence responsive also to variations in steam demand as reflected in changes in exhaust volume.

NEWTON FRANK LANE.
